CLAIM

The ornamental design for a wall mount connecting port for electronic device, as shown and described.

DESCRIPTION

FIG. 1 is a front perspective view of a wall mount connecting port for an electronic device showing the claimed design;

FIG. 2 is a rear perspective view of the wall mount connecting port;

FIG. 3 is a front plan view of the wall mount connecting port;

FIG. 4 is a rear plan view of the wall mount connecting port;

FIG. 5 is a left side elevation view of the wall mount connecting port;

FIG. 6 is a right side elevation view of the wall mount connecting port;

FIG. 7 is a top view of the wall mount connecting port;

FIG. 8 is a bottom view of the wall mount connecting port;

and,

FIG. 9 is a front perspective view of the wall mount connecting port as it appears when mounted on a wall.

The broken lines in FIGS. 1-9 depict portions of the article and form no part of the claimed design. The broken lines in

FIG. 9 depict environmental structure and form no part of the claimed design.

1 Claim, 9 Drawing Sheets
